(57) **CLAIM**

The ornamental design for a fireplace tool, as shown and described.

DESCRIPTION

FIG. 1 is a perspective view of a fireplace tool showing my new design;

FIG. 2 is a side elevation view thereof;

FIG. 3 is a top plan view thereof; and,

FIG. 4 is a bottom plan view thereof.

The dotted lines illustrate portions of the fireplace tool that form no part of the claimed design.

1 Claim, 4 Drawing Sheets
